(57) **CLAIM**

The ornamental design for a bottle, as shown and described.

DESCRIPTION

FIG. 1 is a front left perspective view of a first embodiment of a bottle showing our new design;

FIG. 2 is a left-side elevation view thereof;

FIG. 3 is a right-side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front left perspective view of a second embodiment of a bottle showing our new design;

FIG. 9 is a left-side elevation view thereof;

FIG. 10 is a right-side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The uneven-length dot-dot-dash broken lines in the figures define the bounds of the claimed design and form no part thereof. The even-length dashed broken lines in the figures illustrate portions of the bottle that form no part of the claimed design.

The oblique line shading shown in Embodiment 2 (FIGS. 8-14) is used to denote claimed surfaces of the bottle that are transparent; the details of the opposing sides as seen through the claimed transparent surfaces of the bottle in FIGS. 9-13 have not been shown for ease of illustration and understanding.
